UNITED STATES PATENT OFFICE.

FREDERICK L. PEART AND HARRY M. JONES, OF DENVER, COLORADO.

MINE-CAR COUPLER.

Application filed April 7, 1922. Serial No. 550,450.

To all whom it may concern:

Be it known that we, FREDERICK L. PEART and HARRY M. JONES, citizens of the United States, residing at Denver, county of Denver, State of Colorado, have invented certain new and useful Improvements in Mine-Car Couplers; and we do hereby declare the following to be a full, clear, and exact description of the invention, such as will enable others skilled in the art to which it appertains to make and use the same.

This invention relates to car couplers and particularly to a coupler for use in connection with light railway rolling stock, such as mine cars and the like.

The principal object of the invention is the provision of a device of the character indicated which will be simple in operation and construction, cheap to manufacture owing to its size and lightness of weight, yet at the same time, one that will not accidentally become disengaged or uncoupled under working conditions.

Another object which will be apparent, is its ease of application and safety to the operator when coupling or uncoupling said device, as it requires only one hand to perform these operations, thus distinguishing from the previous types necessitating generally the use of both hands. In using one hand the operator has only the thickness of his shoulders between the cars, which thickness is less than the clearance usually allowed by bumpers on said cars, whereas with the ordinary couplers, necessitating the use of both hands, there is subjected the width of both shoulders to the liability of a squeeze between the cars.

To these ends the invention comprises a coupler bar, preferably flat at its forward end and having a vertical opening therethrough, said bar to be attached to one car, and a cooperating coupler unit adapted to be attached by a flexible connection with an adjacent car, said coupler unit preferably being made as a forging or casting substantially Z-shaped in side elevation, comprising a head section provided with a transverse eye and a substantially flat base, a vertical leg projecting downwardly from the base and a rearwardly extending horizontal leg, the several parts of the unit being so constructed and arranged that when the rearward angular extensions, comprising the legs aforesaid, are passed through the opening in the bar the coupling elements will be se-

curely interlocked automatically, by the head unit dropping to a substantially horizontal position so that the base of the head engages the top of the bar and the upper face of the rearwardly extending leg engages the bottom of the bar and the intermediate vertical leg is engaged in the opening of the bar.

The preferred embodiment of the invention is illustrated in the accompanying drawings in which:

Fig. 1 is a view illustrating the coupler unit suspended from one end of a car or the like in inoperative position.

Fig. 2 is a view in side elevation showing the coupling arrangement as a whole in operative position.

Fig. 3 is a top plan view thereof and Figs. 4 and 5 are end and bottom views, respectively, of the coupler unit per se.

Referring to the drawings in detail the device, as a whole, comprises a coupler unit 1 of substantially reverse Z shape, a cooperating coupling bar 2 carried by one end of a car, and a chain or similar flexible member 3 connecting the coupler unit 1 with the adjoining car by a shackle or the like 4, secured to an appropriate member 5, of said adjacent car.

The coupler unit 1 comprises a head section 6 preferably having a flat base, a lower horizontal leg 7, and a connecting intermediate portion 8, which lower leg portion 7 and intermediate portion 8 are adapted to be inserted in an opening 9, of the proper shape and size to receive these parts, formed in the outer end of the coupling bar 2. The head 6 of the coupler unit 1 is provided with a transverse opening or eye 10, to receive one end of a connecting chain or the like 2. The upper leg or head 6 is also provided with a ring or the like 11 by which the coupler unit 1 and associating chain 3 can be suspended in inoperative position at the end of the car 100 by a hook or the like 12.

In manipulating the device, when it is desired to couple one or more cars together, said cars are moved into proper position so that the necessary slack can be had in the connecting chain 3 or the like, to permit the lower leg 7 and the intermediate portion 8 of the coupling unit 1 to be inserted vertically downwardly into and through the opening 9 of the coupling bar carried by the adjacent car, to be followed by a canting of said coupler unit so that the upper

and lower leg portions 6 and 7, respectively, will assume a horizontal position, which position will normally be maintained by the coupler unit owing to the fact that the upper leg 6 is larger and heavier than the lower leg portion and in addition carries the weight of the connecting chain 3. Under working conditions, as soon as a stress is put on the coupling device this function will be augmented and at the same time the lower leg portion 7, will be forced up against the bottom of the coupling bar 2. From the above it will be noted that the device will not be disengaged or uncoupled accidentally under working conditions, irrespective of whether the said device is stressed, or a certain amount of slack occurs in the connecting chain 3. To uncouple the device it is only necessary to obtain the desired slack sufficient to permit the coupler unit 1 to be moved to a vertical position whereupon an upward movement thereof will withdraw said unit from the coupling bar 2.

25 Although a chain has been illustrated and described for connecting the coupler unit to one of the cars it will be perfectly obvious that any appropriate flexible connection can be substituted therefor. It is also within the scope of the invention to employ a permanent connection for the chain or the like in place of the shackle 4 as shown.

30 As hereinbefore stated the present inven-

tion provides a very simple, yet practical and effective coupling arrangement, in operation and construction, for use in connection with cars or the like of the type indicated.

What we claim is:—

1. A coupler for mine cars and the like comprising a bar having an opening therein, and a cooperating coupling unit including a head and downward and rearward extension from the head adapted to engage and interlock within the opening of said bar.
2. A coupler for mine cars and the like comprising a bar having an opening therein, and a cooperating coupling unit including a head having an eye therein and a flat bottom and downward and rearward extensions from the head adapted to engage and interlock within the opening of said bar.
3. A coupler for mine cars and the like comprising a bar having an opening therein, a cooperating coupling unit including a head and downward and rearward extensions from the head adapted to engage and interlock within the opening of said bar, and a flexible draft member connected to said head.

In testimony whereof we affix our signatures.

FREDERICK L. PEART.
HARRY M. JONES.
